UNITED STATES PATENT OFFICE.

EMILE BRIART, OF JEUMONT, FRANCE.

STEAM-TRAP.

SPECIFICATION forming part of Letters Patent No. 267,831, dated November 21, 1882.

Application filed December 15, 1881. (Model.) Patented in Belgium November 17, 1880, No. 53,054.

To all whom it may concern:

Be it known that I, EMILE BRIART, of Jeumont, in the Department of Nord, in the Republic of France, have invented certain new 5 and useful Improvements in Steam-Traps, of which the following is a specification.

My invention relates to improvements in steam-traps in which the condensed-water reservoir is emptied automatically by the pressure of the steam; and the objects of my invention are, first, to provide a swinging condensed-water reservoir; second, to close the opening where the water flows out instantaneously as the condensed - water reservoir is emptied; 15 and, third, to facilitate the proper adjustment of the closing-valve. I attain these objects by the mechanism illustrated in the accompanying drawings, in which—

Figure 1 is a vertical longitudinal section of 20 the entire apparatus on the line A B; Fig. 2, a top view; Fig. 3, a vertical section of the stand on the line C D; Fig. 4, a detailed horizontal section on the line m n; Fig. 5, a horizontal section of the water-reservoir on the line 25 E F, and Fig. 6 a detailed section of the valve-seat.

Similar letters refer to similar parts throughout the several views.

On the stand V swings a mechanism composed of the hollow globe H, the pipe T, with 30 its vertical prolongation S, and the counter-weight P. The condensed water enters into the apparatus forced in by the pressure of the steam from the pipe G, and passes through the 35 circularly-bent brass pipe L into the globe H, where it is collected till the weight of the water induces the swinging mechanism to go down on this side. By this motion the shaft of the 40 valve J, fixed above the center of the vertical pipe S in the prolongation of its axis by means of a spiral spring, is brought in a straight line with the double-joint piece x and its fulcrum I.

So the force of the spring is obviated and the latter compressed, while the double-joint piece x lifts the valve J from its seat in the neck of 45 the pipe S, and the pressure of the steam forces the condensed water from H through the pipes T and S into the stand V so long till the equilibrium of the swinging mechanism is attained by the counter-weight P. This motion causes 50 the pipe S, and therewith the valve J, to move to one side, whereby the latter, because it is fixed by the double-joint piece x to the screw-bolt I, is drawn downward closing in such way the opening in the neck of the pipe S. The 55 water in the stand V can flow out through the pipe M. Double nuts on the screw-bolt I permit to adjust properly the stop-valve J. The brass pipe L through which the saturated steam enters into the apparatus is bent in such 60 shape as to allow easily the swinging of the collecting-globe H, the pipe T, and the counter-weight P around the fulcrum on the stand V.

Having thus fully described my invention, what I claim, and desire to secure by Letters 65 Patent, is—

1. In steam-traps, the combination of the bent pipe L, the collecting-globe H, the pipes T and S, and the counter-weight P, with the stop-valve J, attached to the stand by means 70 of the double-joint piece x, and the adjustable fulcrum I, substantially as described, and for the purpose specified.

2. In steam-traps, the combination of the stop-valve J with the double-joint piece x and 75 the adjustable bolt I, substantially as set forth.

In testimony that I claim the foregoing I have hereunto set my hand this 29th day of October, 1881.

EMILE BRIART.
